(57) **CLAIM**

The ornamental design for a display screen with animated graphical user interface, as shown and described.

DESCRIPTION

FIG. 1 is a front view of a first image in a sequence of a display screen with animated graphical user interface, showing the new design;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The appearance of the transitional image sequentially transitions between the images shown in FIGS. 1-7. The process or period in which the images transition forms no part of the claimed design.

The broken lines of uneven length show the display screen and form no part of the claimed design.
